Primary Examiner — Susan Bennett Hattan*Assistant Examiner* — Leanne Was(74) *Attorney, Agent, or Firm* — Lerner, David, Littenberg,
Krumholz & Mentlik, LLP(57) **CLAIM**

The ornamental design for a wedge support for camera, as shown and described.

DESCRIPTION

FIG. 1 is a front perspective view of a wedge support for camera showing my new design;
 FIG. 2 is a left side elevation view thereof, the right side being a mirror image thereof;
 FIG. 3 is a back plan view thereof;
 FIG. 4 is a bottom elevation view thereof;
 FIG. 5 is a top elevation view thereof; and,
 FIG. 6 is a back perspective view thereof.
 The broken lines in the drawings depict unclaimed portions of the wedge support for camera and form no part of the claimed design.
